UNITED STATES PATENT OFFICE.

HENRY HIGGIN, OF NEWPORT, KENTUCKY, ASSIGNOR TO THE HIGGIN MANUFACTURING COMPANY, OF NEWPORT, KENTUCKY, A CORPORATION OF WEST VIRGINIA.

WINDSHIELD.

1,371,483.

Specification of Letters Patent. Patented Mar. 15, 1921.

Application filed May 24, 1919. Serial No. 299,398.

To all whom it may concern:

Be it known that I, HENRY HIGGIN, a citizen of the United States, and a resident of Newport, in the county of Campbell and State of Kentucky, have invented certain new and useful Improvements in Wind-shields, of which the following is a full, clear, and exact description, reference being had to the accompanying drawing, forming part of this specification.

My invention relates to wind shields wherein there is provision made for bringing the shield to angled positions. In such shields the lower section is usually employed for ventilation and it is swung inwardly of the body of the vehicle and held in such position so that the air from without is deflected downwardly into the forward part of the car.

One difficulty which is met with in the use of wind shields for ventilation is that insects which strike against the shield are deflected downward into the car thereby causing annoyance. In night driving in the summer the headlights of a motor vehicle tend to attract insects, and the wind shield comes into contact with a great many of them, so that the necessity of some means for excluding them is quite apparent.

It is the object of my invention to provide a screen attachment for wind shields which serves to exclude insects from entrance into the car with the ventilating draft of air. The various points of difficulty which are involved in the employment of a screen for this purpose are provided against according to my invention, as will be noted in the ensuing matter, wherein the means for accomplishing my above stated objects are specifically pointed out and claimed.

In the drawing,

Figure 1 is a perspective view showing the screen in position, but with the wind shield lower section closed.

Fig. 2 is a like view with the lower wind shield section open.

Fig. 3 is a detail side elevation illustrating the method of construction of the screen device.

Fig. 4 is a view of the same parts in vertical section.

The wind shield is shown as having the lower section 1, the upper section 2 and the

side standards 3. It is mounted in the usual manner over the dash 4 of a vehicle, ordinarily a motor vehicle.

In Fig. 2, the lower section of the wind shield is shown as swung angularly inward, thereby leaving a space between its lower edge and the dash, and presenting a deflecting surface to the air tending to direct it through the space between it and the dash, into the inside of the vehicle. As noted heretofore, it is the object of my invention to provide a screen which will protect the space between the lower edge of the shield section and the dash, so as to permit access of air and simultaneously exclude insects.

I form a long narrow screen having frame members 5, crimped over the wire gauze 6. The length of the screen will be such as to completely traverse the air space to be protected, and the width will be such as to take care of the desired width of ventilating opening.

The screen is secured to the lower edge of the lower wind shield section in a resilient manner. This is because when the shield is closed, the screen will be able to take a position somewhat dependent over the dash of the car, and as the section is swung inwardly, it will then be in a position to wipe the upper edge of the dash under pressure from its resilient mounting, thereby preventing rattle and maintaining a tight joint with the dash.

The resilient mounting adopted by me is in the form of spring plates 7 secured to the lower edge of the shield section, and also secured to the inner edge of the screen. As shown in Fig. 3, the screen is in position somewhat dependent from the shield section, as when hanging over the dash, while in Fig. 4 the parts are shown with the screen member pressed upwardly, as by the act of moving the lower end of the screen section into ventilating position.

I mount on the outer edge of the molding or frame of the screen a series of fingers 10, which contact with the dash after the screen has been brought inwardly its full width, and thereby I provide a means for guiding the operator to a correct position for his shield, and also assist in preventing undue vibration and rattle of the screen.

It is believed that the various points of

my invention are apparent without particular description being made of the operation of the device. It will be understood that the claims that follow are not intended 5 to be limited in their construction to exact details of structure as above described, if their language permits of broader interpretation.

Having thus described my invention, what 10 I claim as new and desire to secure by Letters Patent, is:—

1. The combination in a wind shield for vehicles, a section thereof which is capable of taking a position to deflect air into the 15 vehicle between its lower edge and the dash of the vehicle, and a screen resiliently mounted on the lower edge of the section and positioned to wipe the vehicle dash and to fill the space between the dash and the 20 lower edge of the shield section.

2. The combination in a wind shield for vehicles, a section thereof which is capable of taking a position to deflect air into the vehicle between its lower edge and the dash 25 of the vehicle, and a screen resiliently mounted on the lower edge of the section and extending outwardly therefrom and po-

sitioned to wipe the vehicle dash and to fill the space between the dash and the lower edge of the shield section, said screen having stops to limit its inward motion and thus the position of the shield section. 30

3. The combination in a wind shield for vehicles, a section thereof which is capable of taking a position to deflect air into the 35 vehicle, a series of spring fingers secured to the lower edge of said section and projecting outwardly, a screen member mounted on the fingers, said fingers being adapted to maintain the screen member in contact 40 with the dash of the vehicle.

4. The combination in a wind shield for vehicles, a section thereof which is capable of taking a position to deflect air into the vehicle, a series of spring fingers mounted 45 on the lower edge of said screen section, a screen member mounted on the fingers, said fingers being adapted to maintain the screen member in contact with the dash of the vehicle during deflection, and stops on the 50 screen on its edge opposite to the said fingers, to limit the inward movement of the screen together with the said shield section.

HENRY HIGGIN.
